LAMP AND AUTOMOBILE HEADLIGHT

Burton Christmas, Pittsburgh, Pa.

Application May 26, 1931, Serial No. 540,030

3 Claims. (Cl. 240—48.6)

This invention relates to lamps and is herein illustrated as embodied in an automobile headlight.

One serious difficulty with automobile headlights bright enough to adequately illuminate the road or street surface has arisen from the glare of the lights which is sufficient to blind people who face it. Another serious difficulty with bright headlights has arisen from their failure to furnish satisfactory lighting in a fog. The device of the present invention enables these and other difficulties to be overcome.

According to the form of the invention herein disclosed an ordinary parabolic reflector may be provided with a suitable incandescent lamp at its focus, but the bulb of the lamp is shown as provided with a special reflecting surface. This surface may be obtained by providing flat reflecting panels or ribs on the glass of the bulb, said panels running vertically, or by silvering the surface of the bulb over a special area, or by combining the panels with a special silvered area. The devices of the present invention provide a light for lighting the road which spreads fan-like horizontally or downwardly emanating rays. Thus the road is illuminated on both sides and more uniformly than has hitherto been possible. At the same time, the cutting off of the light rays which would go upward, even at a slight 30 diagonal, has cut off the rays which make a bright layer in a fog in front of the driver's eyes and has confined the rays to a space near the ground which is usually nearly free from fog. Other features and advantages will hereinafter 35 appear.

In the accompanying drawings:

Figure 1 is a side view of a vertical section through a reflector and showing the bulb in place.

Figure 2 is a side view of the bulb on a larger 40 scale.

Figure 3 is an end view of the parts seen in Figure 2.

Figure 4 is a top view of the parts seen in Figure 2.

Figure 5 is a horizontal section view from above.

Figure 6 is a horizontal section of a reflector showing the bulb in place, and

Figure 7 is a front view of the bulb in the reflector showing the darkened area near the 50 bottom of the reflector from which no light comes.

A bulb 10 is supported by any desired focusing mount, not shown, in a parabolic reflector 11, of an automobile headlight. For distributing the light coming from the filament more uniformly 55 than has hitherto proved possible, the bulb in-

cludes flat panels or ribs 12, which run vertically around the outer end 13 of the bulb 10 each made by flattening out the slight curvature of the bulb surface, so that it reflects back in the same general direction a beam of more nearly parallel instead of converging rays. As a result the vertical center panels 14, reflect considerable of the light, almost directly back to the parabola 11. The adjacent side panels 15 and 16, also reflect light back mainly, diagonally to the parabola 11, and the side panels, 17, beyond these are successively at greater angles and therefore reflect more of the light and also reflect it further to one side or the other of the center line of the parabola. Since the panels run vertically 60 they spread the light from the filament 18, in a direction which is generally horizontal and is fan like. Moreover, since all the panels are beyond the focus of the parabola they tend to spread the light sideways instead of sending it directly forward, thus illuminating a wide stretch of roadway in front of the car and illuminating that stretch more uniformly than has hitherto been found possible. It is well known that even the most transparent glass reflects back part of the light 70 which strikes its surface instead of transmitting that light, the percentage of reflected light reaching eight per cent as a minimum for light impinging vertically, and rapidly increasing when the light impinges at other angles. As a result 75 of the oblique angle at which most of the light from the filament 18 strikes the upper and lower parts, 18', of the side panels 15, 16 etc., most of that light is ultimately reflected horizontally fan-wise instead of passing up or down clear of the 80 parabolic reflector 11, as is usual and which hitherto has resulted in a loss of the light. In fact, the light which rises upwards shines so brightly in a fog at the front of the automobile, that it blinds the eye of the automobile driver to 85 what is beyond the shining fog at the front of the automobile. Thus, the present invention provides means by which light, which otherwise be lost or which is a handicap on the driver, may be utilized to evenly illuminate the road.

Silvering the bulb end may also cause the bulb to reflect back the whole of the light which would directly strike any eye standing in front of the parabolic mirror. In addition to silvering the end of the bulb it is found advantageous to cut off a part of the light which ordinarily goes from the filament to the lower part of the parabolic mirror because that light is generally reflected slightly upward, blinding the eyes of the person facing the headlight. For this purpose there is illustrat- 100

105

110

- ed a silver reflector 26 covering the round end of the bulb but with its edge inclined at an angle of 60 degrees or little more, the edge of the sil-
 5 vering lying in a plane which only just clears the end of the lower filament. This brings the top edge of the silverying on the bulb just far enough back along the bulb to cut off any direct light rays from the filament which would escape diagonally upward in front of the parabolic mirror.
 10 In the form of the invention herein illustrated, there is no silverying at the bottom of the bulb, the silverying being shown as cut away almost in a half-moon, which in a satisfactory standard bulb was about a half-inch from point 20 to point
 15 21, and has a maximum depth of about three-sixteenths of an inch from a line joining the points. The flat ribs or panels 14, are shown as covering the same area as the silverying, terminating at the edge of the half-moon, while the side panels, 15 and 16 etc., terminate at the edge of the silverying of the bulb, described some distance above. The unsilvered half-moon 19, allows direct light from the filament 17, to fall on the bottom of the parabolic mirror, both behind the filament and up
 20 to a point directly below the lamp filament, but allows almost no light to reach the lower front part 22, of the parabolic mirror, with the result that the parabolic mirror is dark over an area 23, about an inch and a half wide and slowly narrowing, for the most part, practically up to the vertical sides, 24. As a result of this darkened area 23, and the bright area 25, behind it, it is found that the roadway is illuminated by a light which cannot blind a person of normal height
 25 standing in front of the automobile.
 30 Having thus described certain embodiments of the invention, what is claimed is:
 1. The combination with a headlight reflector having a parabolic mirror, of an electric bulb having a filament, glass walls on the bulb forming a smooth curve from the base outward, the
 35 opposite end of the bulb having nearly flat panels of substantial area running vertically and covering most of the end and conforming fairly closely to a smooth curve so as to reflect back into the parabolic mirror rays of light from the filament 80 which spread horizontally, and a mirror covering the panels and terminating at their ends.
 2. The combination with a headlight reflector having a parabolic mirror, of an electric bulb having a filament at the focus of the mirror and lying well back of the forward edges of the mirror, glass walls on the bulb forming a smooth curve from the base outward to about a plane passing through the filament and cutting the mirror on all sides, the opposite end of the bulb having nearly flat panels of substantial area running vertically and covering all the area beyond the plane and conforming fairly closely to a smooth curve so as to reflect back into the parabolic mirror rays of light from the filament which 90 spread horizontally, and a mirror covering the panels and terminating at their ends.
 3. The combination with a headlight reflector having a parabolic mirror, of an electric bulb having a filament at the focus of the mirror and 100 lying well back of the forward edges of the mirror, glass walls on the bulb forming a smooth curve from the base outward to about a plane cutting the mirror near its front upper edge and passing through the filament, the opposite end of the bulb having nearly flat panels of substantial area running vertically and terminating at said plane except at the bottom, and an extension of the smooth curve between bottom panels forming a smooth area below the filament so 110 that undistorted light reaches the mirror from the bottom of the filament, and a mirror covering the panels and terminating at their ends.
